UNITED STATES PATENT OFFICE.

OTIS T. GREGG, OF HACKENSACK, NEW JERSEY, ASSIGNOR TO THE GREGG COMPANY, LIMITED, OF NEWBURGH, NEW YORK, A CORPORATION OF NEW YORK.

SELF-CENTERING ROLLER-BEARING.

1,246,589.

Specification of Letters Patent. Patented Nov. 13, 1917.

Application filed April 2, 1914. Serial No. 829,080.

To all whom it may concern:

Be it known that I, Otis T. GREGG, a citizen of the United States, and a resident of the village of Hackensack, county of Bergen, and State of New Jersey, (whose post-office address is Hackensack, N. J.,) have invented a new and useful Improvement in Self-Centering Roller-Bearings, which invention is fully set forth in the following specification.

The devices of this invention are intended primarily to be secured upon trucks of cane-cars or the like, to act as side-bearings for the bolsters, but may be employed as anti-friction bearings in other locations. Broadly, the invention comprises a "floating" (or unpivoted) roller in combination with means for normally maintaining the roller in intermediate or other predetermined position in its pathway, such means consisting preferably of a rocking-member that rocks like the rockers of a rocking-chair; and one object of the invention is to restore the roller to its intermediate or normal position, without raising or lowering the level of the roller. Another feature of the invention consists of a suitable housing. And the invention comprises also various features of construction and arrangement hereinafter set forth and claimed.

The invention may be embodied in various forms, but for convenience one preferred embodiment will be described in connection with the accompanying drawings.

In these drawings

Figure 1 is an end view of a truck and bolster provided with two of the new self-centering roller-bearings;

Fig. 2 shows, on a much larger scale a vertical section taken longitudinally through one of the preferred embodiments of the device; and

Fig. 3 is a vertical section taken through the line III—III of Fig. 2.

Referring first to Fig. 1, 1 represents the truck-beam, upon which is pivoted the bolster 2, as is well understood. At each end of the truck is secured a suitable housing 3, in which is carried the self-centering roller 4. Referring to Figs. 2 and 3, the roller 4 rests upon the centering device or rocker 5, which latter is preferably but not necessarily a symmetrically-curved plate of uniform thickness as shown. It will be observed that the roller is not pivoted, but is

free to roll to and fro over the rocker 5, which latter is adapted to roll to-and-fro upon an ever-shifted fulcrum like the rockers of a rocking-chair. It will be further understood that if the roller should happen to be on either end of the rocker the weight and leverage of the other end thereof would tend to restore the roller to the normal intermediate position indicated in Fig. 2.

To guide and limit the movements of the roller and rocker, it is preferable to have some form of suitable housing, such as 3, whose sides may be cut away, as at 6, to leave the vertical margins 7; while in the top of the housing is a longitudinal slot, to receive the roller, defined on each side by the overhanging lips 8. At one end of the housing is an opening 9 for permitting endwise insertion of the rocker. The floor of the housing, adjacent this opening, may be beveled off as shown. The roller 4 is first inserted from the top, through the longitudinal slot referred to, until its center is below the margin 7, whereupon the transverse pin 10 is inserted through a hole in its center; then the rocker 5 is introduced through the end-opening 9, after which if necessary a sufficient number of spacing-plates may be similarly inserted beneath the rocker. Thereby the roller is raised into the operative position indicated in the drawings, with the projecting ends of its pin 10 lying just beneath the horizontal lips 8 and terminating adjacent the side-margins 7, while its own periphery is exposed above the level of the top of the housing. Spacing plates 11 may be introduced under rocker 5 or other adjusting means employed to effect any desired adjustment of the height of the roller 4. The opening 9 may be closed by any suitable means, as a stout transverse bolt 12, passed through suitable holes in the sides of the housing and secured in place by a cotter-pin 13. The housing may be secured upon the truck (or other desired location) by means of screws or bolts passing through flanged feet 14.

The operation of the device is obvious. When the car turns in either direction (as upon a curving track), one of the overhanging ends of each bolster will contact with its corresponding roller 4, thereby causing the roller to travel toward one end of the pathway defined by the particular housing (or other limiting-means). em. 110

ployed, without raising or lowering the level of the roller; but when the bolsters no longer contact with their rollers, each balanced rocker 5 tends to restore its roller to its normal intermediate position, or to restore it if any jolting has displaced it.

Should a pivoted roller be employed, there is liable to be considerable rubbing (and consequent friction) of its spindle and of the bearing therefor, and the spindle itself is liable to be broken. When, however, the "floating" roller of the present invention is employed, there is no rubbing-action either between the roller and the surface which supports it or between the roller and the surface which bears upon it; hence friction is very greatly reduced and the life of the device is prolonged.

Again, should such floating roller be employed upon an ordinary flat pathway, it is liable to be jolted to one end or the other of its pathway; whereas it should normally remain at an intermediate position (beneath the bolster). When, however, the rocker 5 is employed, if the roller should be jolted toward one end thereof, the gravity and leverage of the other end of the rocker tends to restore the roller to its normal intermediate position.

It will be understood that various forms of housing are available, and indeed that a "housing" may be dispensed with so long as suitable means are employed to guide and limit the movements of the roller and the rocker. It will further be understood that the rocker need not be of the exact shape indicated, and its contour might consist of broken lines rather than a continuous curve as shown. Again, the drawings show only one particular manner of securing the roller in place (as by the detachable transverse pin 10 coöperating with the side-margins 7 and lips 8), although many other expedients might be used for the purpose. Also, some other adjusting means might be employed (in place of the plates 11) to hold the rocker and the roller at the desired level; and some

means other than the bolt 12 might be employed for closing the opening 9. In short, the essence of the broad invention consists of the combination of the floating roller and the automatically-centering rocking-member upon which it rolls and which serves in and of itself to restore the roller to its central position; and everything else is ancillary and incidental to the main invention, and is almost a matter of choice so long as the main idea is employed.

The invention having been thus described, what is claimed is:

1. A self-centering roller-bearing, comprising a housing having at its top a longitudinal slot defined by overhanging lips and down-turned marginal sides, said housing having an opening at one end, a concavo-convex rocker adapted to rock longitudinally in said housing, a roller located in said slot and resting freely upon said rocker and carrying centrally a detachable pin whose ends lie beneath said lips and terminate adjacent said marginal sides, a plurality of spacing-plates beneath said rocker, and a detachable pin constituting a gate for closing said opening.

2. A self-centering roller-bearing, comprising a housing having at its top a longitudinal slot defined by overhanging lips and down-turned marginal sides, said housing having an opening at one end, a concavo-convex rocker adapted to rock longitudinally in said housing, a roller located in said slot and resting freely upon said rocker and carrying centrally a detachable pin whose ends lie beneath said lips and terminate adjacent said marginal sides, and a detachable pin constituting a gate for closing said opening.

In testimony whereof I have signed this specification in the presence of two subscribing witnesses.

OTIS T. GREGG.
